(57) CLAIM

The ornamental design for an electric stapler, as shown and described.

DESCRIPTION

FIG. 1 is a top plan view of an electric stapler showing our new design;

FIG. 2 is a rear plan view thereof;

FIG. 3 is a right side perspective view thereof;

FIG. 4 is a bottom plan view thereof;

FIG. 5 is a right side plan view thereof;

FIG. 6 is a front plan view thereof; and,

FIG. 7 is a left side plan view thereof.

The broken lines illustrate portions of the electric stapler that form no part of the claimed design.
